AUTOMATIC SAFETY FUEL SYSTEM

David Samiran, Fairfield, Ohio

Application July 31, 1940, Serial No. 348,969

27 Claims. (Cl. 158—36)

(Granted under the act of March 3, 1883, as
amended April 30, 1928; 370 O. G. 757)

The invention described herein may be manufactured and used by or for the Government for governmental purposes, without the payment to me of any royalty thereon.

The present invention relates in general to fuel systems provided with a plurality of separate fuel sources and more particularly to fuel systems in which the contents of a plurality of fuel containers are automatically connected in predetermined order to a source of fuel consumption, such as an airplane engine or the like, the present application being a continuation in part of my copending application Serial No. 261,542, filed March 13, 1939.

In fuel systems having selector valves rotated by an electric motor or the like, it is desirable to have the valve rotated slowly so that it can be promptly stopped when the desired ports are in exact registry with each other. If the selector valve rotates slowly throughout its operating cycle, however, considerable time periods of delay are experienced when passing through successive positions of the selector valve, during which periods of time fuel is shut off through the valve and the fuel pump is therefore unsupplied with fuel. From this standpoint, it is desirable to have the selector valve rotate quickly from one position to the next and the two desirable characteristics just considered are obviously in conflict with each other and constitute a failure of the ordinary type of automatically operable selector valve.

It is therefore an object of my present invention to provide a selector valve operating mechanism wherein the motor for operating the selector valve may be normally operated at high speed to minimize the period of time between successive selector valve positions and to provide means to slow down the rotation of the motor as the ports of the valve approach a registering position whereby the valve can be promptly and accurately stopped at the registering position.

A further object is to provide means in the form of an electrically operated clutch for the purpose of effecting exact registration of the selector valve ports, whereas there is a possibility of their overrunning as a result of momentum of the motor after it is deenergized if such clutch were not provided.

Still a further object is to provide, in connection with a motor operated selector valve wherein the motor is controlled by a fuel pressure responsive switch, a means to open the circuit of the switch at the completion of a selector valve

operation through the medium of a solenoid or the like, so that the fuel pressure responsive switch may be conveniently located remotely with respect to the selector valve operating mechanism and synchronous operation effected through electric wiring connections to the solenoid.

Still a further object is to provide an automatic fuel system having a safety feature in that, 10 when the selector valve rotates to any position corresponding to a fuel tank that is inadvertently empty, or empty as a result of a bullet hole leak or the like, the selector valve will move on to the next fuel tank containing fuel without 15 stopping at the empty tank position.

Another object is to provide a switch in connection with each fuel tank operable to render the mechanism that slows down the valve at registering position ineffective, so that the selector valve will be quickly moved on past an empty tank position without the operation being slowed down as when effecting registration of the selector valve ports when the tank to which the selector valve is being adjusted contains fuel.

Still another object is to provide a fuel system including a selector valve and operating mechanism therefor wherein the valve is rotated at high speed between successive positions to cut time loss to a minimum between adjustments 20 of the selector valve to new sources of fuel supply and a fuel tank switch on each fuel tank cooperating with a commutator on the selector valve to shunt out a resistance which, when not so shunted, slows down the motor at selector 25 valve registering positions.

Other objects and advantages of my invention will become apparent from the following description taken in connection with the accompanying drawings, it being clearly understood 30 that the same are by way of illustration and example only and are not to be taken as in any way limiting the spirit and scope of my invention, which are to be limited only by the prior art and by the terms of the appended claims.

Referring to the drawings, in which numerals of like character designate similar parts throughout the several views:

Figure 1 is a diagrammatic representation of an automatic safety fuel system embodying my 40 invention:

Figure 2 is a diagrammatic view of the fuel pressure responsive switch of my system showing it in a position assumed as a result of fuel pressure drop;

Figure 3 is a similar view of the switch showing

it in the position assumed as a result of subsequent building up of fuel pressure therein;

Figure 4 is a similar view of a portion of Figure 1 showing a pair of cams and a commutator of my system in a different position as assumed when the selector valve has rotated nearly to its next successive position with respect to that shown in Figure 1, and

Figure 5 is a sectional view through a selector valve of my system showing different positions thereof for movement between successive selector valve positions and port registering positions.

In the accompanying drawings, I have used the reference characters 1, 2 and 3 to indicate fuel tanks. Three tanks are shown merely by way of illustration, as, obviously, a greater or less number thereof may be provided without departing from the spirit of my invention. The fuel tanks 1, 2 and 3 are illustrated as piped by conduits 4, 5 and 6 to inlet bosses 7, 8 and 9, respectively, of a selector valve 10. The selector valve 10 has a rotatable valve plug 12 provided with an L-shaped passageway 13 adapted to connect any one of the inlets 7, 8 or 9 with an outlet conduit 14.

The conduit 14 extends to a fuel strainer 15, the outlet of which is connected to the inlet of an engine-driven fuel pump 16. The shaft thereof, driven by the engine, is indicated at 17. The outlet of the filter 15 is also connected with the inlet of a manually operable wobble pump 18.

The outlet of the pump 17 is connected through a switch pressure regulator 19 to an inlet pipe 20 of an air-vapor eliminator 21. The outlet of the wobble pump 18 is also connected to the inlet pipe 20.

The air-vapor eliminator 21 has a connection 22 in the form of a conduit for conveying fuel to a fuel injector 23. The fuel injector includes a pressure relief valve 24 through which fuel in excess of the requirements of the injector 23 is returned through a conduit 25 to the intake of the pump 16. The eliminator 21 has an air-vapor outlet 26 for discharging air and vapor eliminated from the fuel within the eliminator 21. The air and vapor are returned to one of the tanks, such as 3, thereby permitting any fuel condensing from the vapor to return to the fuel supply. The switch pressure regulator 19 and the air-vapor eliminator 21 are described in my copending application above referred to, and form no part of my present invention but are illustrated merely to show how the present fuel system may be connected with an engine or other fuel consuming device. In some types of engines a carburetor would be substituted for the fuel injector 23.

For operating the selector valve 10 I provide a shaft 27. The shaft 27 has secured thereto a gear 28 which meshes with a pinion 29 suitably journaled for rotation. The pinion 29 is provided with clutch teeth 30 with which, at times, a toothed face of a clutch disc 31 is adapted to cooperate. The clutch disc 31 is mounted on a square shaft 32 which is pressed as by a spring 33 in the proper direction for normally disengaging the clutch disc 31 from the clutch teeth 30 of the pinion 29.

The square shaft 32 is slidably and non-rotatably associated with a bevel gear 34 suitably journaled for rotation by a motor M. The motor M has a bevel pinion 35 secured to its shaft and meshing with the bevel gear 34 for this purpose.

For engaging the clutch disc 31 with the clutch teeth 30 of the pinion 29, I provide a solenoid 36

in which is slidably mounted a plunger 37. A stem 38 extends from the plunger 37 and is adapted to engage the back of the clutch disc 31, so that whenever the solenoid 36 is energized the shaft 32 will be forced in a left-hand direction against the tension of the spring 33.

For controlling the motor M, I provide a fuel pressure responsive switch S. The switch S has a bellows chamber 39, in which is mounted a collapsible bellows 40. The bellows 40 collapses against the tension of a spring 41 and thereby actuates a stem 42 in a left-hand direction. A conduit 43 extends from the bellows chamber 39 to the switch pressure regulator 19, which regulator furnishes fuel under a substantially constant pressure to the conduit 43 as long as the pump 16 is receiving a predetermined quantity of fuel or fuel in excess of such quantity. When the pump 16 runs out of fuel, then the pressure drops within the bellows chamber 39 so that the spring 41 retracts the stem 42.

The stem 42, whenever the bellows is collapsed by suitable fuel pressure acting within the bellows chamber 39, is adapted to move a switch carriage consisting of a supporting bar 43a and a pair of sliding guide rods 44 in a left-hand direction, as in Figures 1 and 3. The supporting bar 43a has a pair of ears 45 to which is pivoted a switch arm 46 having a telescoping spring-urged extension 47. The extension 47 carries a metallic roller 48 adapted at times to bridge a pair of contacts 49 and 50, as shown in Figures 1 and 2. The roller 48 and the contacts 49 and 50 are suitably insulated from the remaining parts of the switch S.

When the fuel pressure drops within the bellows chamber 39, the switch carriage 43a-44 will be moved in a right-hand direction by the spring 41, whereupon closure of the circuit across the contacts 49 and 50 is effected, as in Figure 2, by the switch arm 46 engaging a stationary stud 51. Such engagement causes the roller 48 to move outwardly relative to the contacts 49 and 50 and bridge them.

The construction of the switch S is such that mere movement from the position of Figure 2 to the position of Figure 3 will not open the circuit through the switch parts 49-48-50. When the switch arm 46 and the switch parts just referred to are in the position of Figure 3, the switch can subsequently be opened by a solenoid 52 having a plunger 53 and a stem 54 connected therewith and terminating in a cam lobe 55. The cam lobe 55 is adapted to move from the position of Figure 3 to the position of Figure 1, thereby engaging a companion cam lobe 56 of the switch arm 46 to swing the switch arm to open circuit position whenever the solenoid is de-energized. Such de-energization of the solenoid permits a spring 57 on the stem 54 to effect the above described circuit opening movement of the stem and thereby of the switch arm 46, whereas whenever the solenoid 52 is energized the plunger 53 is drawn into the solenoid against the tension of the spring 57 to remove the cam lobe 55 from registry with the cam lobe 56, as shown for instance by dotted lines in Figure 2 and in Figure 3.

As before stated, the switch S is provided for controlling the motor M. The circuit for this purpose includes a source of current supply such as a battery 58 having one side grounded and the other side connected through an ignition switch 59 with the switch contact 50. The wires in this circuit are as follows: 60, 61, 62 and 63. The wires 62 and 63 are connected together at a

negative terminal 64 of a terminal panel 65. The ignition switch 59 is the one used for the ignition system of the engine on which my fuel system is installed, an ignition wire 66 extending from the switch to the ignition system. I connect the ignition switch 59 in the circuit of my fuel system in this manner so that there can be no undesired operation of the fuel system during a time when the engine is not running, because of the ignition switch being turned off, and accordingly operation of the fuel system is not needed.

The terminal panel 65 has a control terminal 67 with which the contact 49 of the switch S is connected by a wire 68. From the control terminal 67 a wire 69 leads to a resistance shunting switch having a stationary contact 10 and a movable contact 71. The contact 71 is connected by a wire 72 to one side of the motor M, the other side of which is grounded by a wire 73.

I provide a resistance element 74 shunted by the switch 70—71, so that whenever the switch is open the resistance element is in series with the motor M, thereby slowing down its rotation for a purpose which will hereafter appear. To operate the switch 70—71, I provide a cam disc 75 on the shaft 27 having cam lobes 75a, 75b and 75c. These are adapted to successively cooperate with a cam lobe 76 of the switch contact 71 to lift it from engagement with the contact 70 whenever any of the lobes 75a, 75b or 75c registers with the lobe 76.

The solenoid 52 is also controlled by the switch S through a wire 77 connected with the control terminal 67, normally opened switch contacts 78 and 79, a wire 80 and a ground wire 81. Thus although the solenoid 52 is under control of the switch S, it can be energized only when the contacts 78 and 79 are also engaged.

The contacts 78 and 79 are controlled by a cam disc 82 having notches 82a, 82b and 82c. The notches are adapted to successively receive a cam lobe 83 of the switch contact 79 to open the circuit across it and the contact 78. Rotation of the shaft 27 on which the cam disc 82 is mounted to a position other than registry of any of the notches with the lobe 83 results in closure of the circuit for the solenoid 52.

In addition to the resistance 74 being shunted by the switch 70—71, it is also shunted by contacts 84 and 85 of a relay R. The contact 84 is connected by a wire 86 to one end of the resistance element 74, while the contact 85 is connected by a wire 87 to the other end thereof.

The relay R has a coil 88 connected by a wire 89 to the control terminal 67 and by a wire 90 to a three-pole commutator blade 91. The commutator blade 91 coacts with commutator segments 92a, 92b and 92c of a commutator drum 92. Individual blades 93, 94 and 95 are connected by wires 96, 97 and 98 to float switches 99, 100 and 101 located at the fuel tanks 1, 2 and 3, respectively. Each float switch includes a suitable float 102 responsive to the level of fuel in the tank and so connected with the float switch that when the fuel tank is nearly empty, as in the tank 1 of Figure 1, the float switch is nearly closed, such closing occurring just before the float rests on the bottom of the tank. In this manner each tank when empty effects closure of its float switch so that a circuit may be established from either of the wires 96, 97 or 98 to ground wires 103, 104 or 105, respectively, of the float switches 99, 100 and 101.

My fuel system may include an indicator light 106 connected by a wire 107 to the control ter-

5 minal 67 and a wire 108 to ground. Thus the indicator light 106 is energized any time the switch S is closed. For testing the indicator light 106, a manual testing switch 109 is provided connected by wires 110 and 111 between the negative terminal 64 and the indicator light.

It is desirable in an automatically operable selector valve of the character herein disclosed, to permit manual rotation of the valve to any fuel tank or to "off" position. For this purpose I provide a control handle 112 on the selector valve shaft 27 having a pointer 113 cooperating with a dial 114. The dial 114 may be inscribed with "1, 2, 3" and "off," indicating the respective fuel tanks with any one of which the selector valve may be connected, and "off" position when none of the fuel tanks are connected through the selector valve with the pump supply conduit 14. The handle 112 may be operated either clockwise or counterclockwise any time desired, inasmuch as the solenoid 36, normally de-energized, results in the clutch connection 30—31 being inoperative. In the event that the solenoid is energized, the handle 112 can still be rotated as desired, as the clutch teeth, held engaged by the solenoid, can ratchet past each other.

Practical operation

Assuming a fuel level in the tank 1 as shown in Figure 1, and that further fuel is then pumped from the tank, the float 102 therein will lower and close the float switch 99. A circuit can now be traced from the ground wire 103 of the float switch 99 through elements 96, 92a, 91, 90, 88, 89, 67, and 68 to the switch contact 49. The switch S, however, is open so that there is no current flow. Accordingly, the pump 16 may continue to operate for draining substantially all of the fuel from the tank 1.

When the pump 16 runs out of fuel it can no longer keep pressure up in the switch pressure regulator 19 and the conduit 43 leading to the bellows chamber of the switch S. Therefore the spring 41 expands the bellows 40 and moves the switch carriage to the right, as in Figure 2, thus closing the switch S. Closure of the switch S energizes the control terminal 67 from the battery 58 through the following elements: 61, 59, 62, 63, 50, 48, 49 and 68. Therefore the relay coil 88 is energized for attracting the armature of the relay and thereby closing the contacts 84 and 85 which, however, produces no result, since the resistance element 74 is already shunted out of the motor circuit by the switch 70—71.

Closure of the switch S, in addition to the relay circuit just described, establishes three other circuits as follows: (1) a circuit for the motor M from the control terminal 67 through elements 69, 70, 71, 72 and 73; (2) a circuit for the solenoid 52 from the control terminal through elements 77, 78, 79, 80 and 81, the solenoid however remaining de-energized until the motor M has rotated the shaft 27 sufficiently for the cam notch 82 to coact with the lobe 83 and close the contacts 78 and 79. Thereupon the cam lobe 55 of the solenoid 52 will move from the full line to the dotted position of Figure 2; (3) the clutch solenoid 36 will be energized by current from the control terminal 67 through a wire 115 and a ground wire 116. Thus, as soon as the motor M starts to operate, the clutch solenoid is energized to operatively connect the motor with the selector valve.

With the solenoids 36 and 52 energized and the motor M operating, the selector valve will

rotate from the full line position shown in Figure 5, with the port 13 of the valve plug 12 in registry with the conduit 4 of the tank 1 to a position where the port 13 starts to register with the next successive conduit 5 (shown by dotted lines). The angle of travel is indicated by the dimension line 117.

As soon as the segment 92a of the commutator 92 leaves the commutator blade 91, the relay coil 88 will be de-energized, and if the fuel tank 2 contains sufficient fuel to position the float switch 100 in its open circuit position, the relay will not be re-energized when the commutator segment 92b bridges the blades 91 and 94 (as shown in Figure 4). When the angle of movement 117 has been completed, the next cam lobe 75b will open the switch 70-81, thereby opening the shunt circuit therethrough for the resistance element 74 and the motor circuit will then be through the resistance element instead of directly across the closed switch contacts 70 and 71. This effects slowing down of the motor M so that during the angle of movement indicated at 118 in Figure 5, while the port 13 is being aligned with the conduit 5, there will be slow enough movement to permit the port to stop in exact registry with the conduit as soon as the motor M and the clutch solenoid 36 are de-energized.

During the movement of the selector valve port 13 through the angle 118, fuel is being picked up from the tank 2 by the pump 16 and thereby building up pressure within the bellows chamber 39. The switch carriage 43-44 will accordingly be carried from the position of Figure 2 to the position of Figure 3, with the switch 49-48-50 still in closed position. Finally, when the port 13 is in exact registry with the conduit 5, the lobe 83 of the switch blade 79 will drop into the notch 82b, thus de-energizing the solenoid 52, causing it to quickly move to the position of Figure 1 for opening the switch S. This results in de-energization of the control terminal 67 and subsequently de-energization of the motor M and the clutch solenoid 36. De-energization of the selector valve insures instant stopping of the selector valve without any possibility of overrun as might occur if the selector valve were directly connected with the motor and thereby subject to motor overrun after the motor has been de-energized. At about the same time that the lobe 83 of the switch blade 79 drops into the notch 82b, the lobe 76 of the switch blade 71 drops behind the lobe 75b of the cam disc 75, thus positioning the switch 70-71 for a subsequent operation.

From the foregoing description of the operation of my fuel system, it is obvious that the selector valve operating motor, during the shift of selector ports for registration with successive tanks, is speeded up for rapid movement between ports and is then slowed down as the ports are approaching alignment. The ports of the valve are thus gradually brought into registration and may be accurately stopped at registering position.

However, time delay as would be caused by slow movement from one port to the next is eliminated, thus speeding up the change-over from an empty tank to the next tank. Thus I secure both the advantage of quick movement from one position to the next and slow movement for port registration purposes.

When, however, the next tank, as for instance the tank 2, is empty, it is desirable to go on to the third tank which, without the relay R, the 75

commutator 92, and the float switches 99, 100 and 101, would occur because the absence of fuel from the tank 2 would permit the fuel pressure in the switch S to remain low because there would be no fuel from the tank 2 for the pump 16. Accordingly, the switch S would remain in the position of Figure 2 instead of being carried out to the position of Figure 3, and when the lobe 83 of the switch blade 79 dropped into the notch 82b, de-energization of the solenoid 52 would cause the lobe 55 to move from the dotted position of Figure 2 to the full line position without opening the switch S. Therefore there would be continued rotation of the motor M as it is controlled by the switch S, but the rotation would be slowed down at the conduit 5 because the cam lobe 75b would open the resistance shunting switch 70-71.

Such slowing down of the motor introduces undesirable delay, as since the tank 2 is empty it is desirable to go on at high speed to the tank 3. Therefore the float switches, the commutator and the relay arrangement has been provided and enter into the operation as follows: If the tank 2 is empty, its float switch 100 will be closed. Accordingly, when the commutator segment 92 bridges the commutator blades 91 and 94, the relay coil 88 will be energized because the control terminal 67 is already energized by the switch S. This results in closure of the relay R so that, regardless of any opening of the switch 70-71, the resistance element 74 will be shunted out of the motor circuit, which circuit whenever the switch 70-71 is opened may be traced as follows: from the control terminal 67 through elements 69, 86, 84, 85, 87 and 72 to the ground wire 73. Thus the slowing down for port registration will be eliminated whenever an empty tank is encountered and high speed rotation of the selector valve will continue through all positions corresponding to empty tanks and be slowed down and stopped only when a full tank position is encountered. This cuts down time loss to a minimum for obtaining a new fuel supply source. One of the fuel tanks may be empty from neglect or from a leak, such as a bullet hole, under which circumstances the selector valve is automatically caused to pass by the empty tank without any loss of time, which under any circumstances is desirable to prevent any missing of the motor caused by an insufficient fuel supply.

During the time that the selector valve is being adjusted from one selector valve position to another one, a reserve supply of fuel in the air-vapor eliminator 21 is being used and the eliminator is designed of such capacity as to take care of a shift through several selector valve positions. Obviously, the shorter periods of time there are between positions when empty tanks are encountered, the smaller will be the volume requirements for the reserve supply in the eliminator 21. The commutator segments 92a, 92b, 92c, are of sufficient length to pick up and close the relay circuit prior to opening of the switch 70-71, thus insuring that at no time will the motor be slowed down if an empty tank is encountered.

The switch S may be operated directly from a cam on the shaft 27, as shown in my copending application. The use of a solenoid 52 for operating it indirectly, as in my present application, permits mounting of the switch S and the solenoid at a position remote from the selector valve. The solenoid provides an instantaneous switch opening action for breaking the circuit through

the switch S if, before the lobe 83 drops into any of the notches of the cam disc 82, the fuel pressure has been built up within the switch S to move it from the position of Figure 2 to the position of Figure 3. Failure to build up such a pressure results in a recycling circuit being established to cause operation of the selector valve on past an empty tank position resulting from the pump 16 receiving air instead of fuel from said empty tank.

Any time that the operator wishes to test the indicator light 106, he may do so by manually closing the switch 109, thus providing a circuit for the indicator light 106 from the battery 58 through elements 61, 59, 62, 64, 110, 109, 111, 106 and 108 to ground. He is thus assured that current supply to automatically operate the selector valve is available and that his indicator bulb is not burned out, so that any subsequent fuel failures occurring as a result of fuel tanks becoming empty will be indicated to him by flashing on of the light 106 under control of the switch S. As soon as a selector valve operation has been completed, then the light will be extinguished due to opening of the switch S. During selector valve operation, the indicator 113 will indicate on the dial 114 what tanks are being connected to the pump and which are empty and passed up by the automatic selector valve operating mechanism.

Some changes may be made in the construction and arrangement of the parts of my device without departing from the real spirit and purpose of my invention, and it is my intention to cover by my claims any modified forms of structure or use of mechanical equivalents which may be reasonably included within their scope without sacrificing any of the advantages thereof.

I claim as my invention:

1. In an automatic safety fuel system having a plurality of fuel tanks, a selector valve operable to selectively connect any one of said plurality of fuel tanks with a fuel consuming device, means for operating said selector valve at relatively high speed when changing from one selector valve position to the next, a fuel pressure responsive controller for controlling said means, means for slowing down the operation of said first means when said selector valve has progressed to a position adjacent alignment of its ports, a control device for each fuel tank and operable when the tank is empty to render said means for slowing down the operation of said first means ineffective, said control device being operatively connected with said selector valve to effect such rendering of said first means ineffective only when that tank, for a selector valve position assumed by the selector valve, is empty.

2. In an automatic safety fuel system having a plurality of fuel tanks and a fuel pump, a selector valve connected between said plurality of fuel tanks and said fuel pump, said fuel pump being operative to pump fuel to a fuel consuming device, a motor for operating said selector valve at relatively high speed when changing from one selector valve position to the next, a fuel pressure responsive switch for controlling said motor, means for slowing down the operation of said motor when said selector valve has progressed to a position adjacent alignment of its ports, a switch for each fuel tank and operable, when the tank is empty, to render said means for slowing down the operation of said motor ineffective, and a commutator operatively connected with said selector valve and electrically connected in the circuits of said tank switches to

effect such rendering of said means for slowing down the operation of the motor ineffective only when that tank is empty which corresponds to a selector valve position assumed by said selector valve.

3. In an automatic safety fuel system having a plurality of fuel tanks and a fuel pump operative to pump fuel to a fuel consuming device, a selector valve, a motor for operating said selector valve at relatively high speed when changing from one selector valve position to the next, a fuel pressure responsive switch for controlling said motor, said selector valve, in a predetermined position, effecting opening of said switch, means for slowing down the operation of said motor when said selector valve has progressed to a position adjacent alignment of its ports comprising a resistance element in series with said motor, a shunting switch for said resistance element and a cam rotatable with said selector valve to open said switch, a switch for each fuel tank and operable, when the tank is empty, to shunt said shunting switch for slowing down the operation of said motor, and a commutator operatively connected with said selector valve and electrically connected in the circuits of said tank switches to effect such shunting of said shunting switch only when that tank is empty which corresponds to a selector valve position assumed by said selector valve.

4. In an automatic safety fuel system having a plurality of fuel tanks and a fuel pump operative to pump fuel to a fuel consuming device, a selector valve, an electric motor for operating said selector valve at relatively high speed when changing from one selector valve position to the next, a fuel pressure responsive switch for controlling said motor, a resistance element connectible in series with said motor for slowing down the operation thereof when said selector valve has progressed to a position adjacent alignment of its ports, a switch for each fuel tank and operable when the tank is empty to shunt said resistance element out of the motor circuit for slowing down the operation of said motor while said ports are being aligned, and a commutator operatively connected with said selector valve and electrically connected in the circuits of said tank switches to effect such resistance element shunting only when the tank for a given selector valve position is empty.

5. In an automatic safety fuel system having a plurality of fuel tanks, a selector valve operable to selectively connect any one of said plurality of fuel tanks with a fuel consuming device, a prime mover for operating said selector valve at relatively high speed when changing from one selector valve position to the next, a fuel pressure responsive controller for controlling said prime mover, means for slowing down the operation of said prime mover when said selector valve has progressed to a position adjacent alignment of its ports, and means to render said means for slowing down the operation of said prime mover ineffective, said last means being operatively connected with said selector valve to effect such rendering of said prime mover ineffective only when that tank, for a selector valve position assumed by the selector valve, is empty.

6. In an automatic safety fuel system having a plurality of fuel tanks and a fuel pump, a selector valve for selectively connecting any one of said plurality of fuel tanks with said fuel pump, said fuel pump being operated to pump fuel to a fuel consuming device, a shaft for said selector

valve, a motor for rotating said shaft at a relatively high speed when changing from one selector valve position to the next, a fuel pressure responsive switch for controlling said motor and thereby the rotation of said shaft, a cam on said shaft cooperating with said fuel pressure switch to open the switch when the shaft assumes a position of alignment of the ports of the selector valve providing fuel pressure has been built up in said fuel pressure switch, means for slowing down the operation of said motor when the selector valve has progressed to a position adjacent alignment of its ports, a switch for each fuel tank and operable when the tank is empty to render said last means ineffective to slow down said motor, and a commutator on said shaft and electrically connected in the circuits of said tank switches.

7. In an automatic safety fuel system having a plurality of fuel tanks and a fuel pump operative to pump fuel to a fuel consuming device, a selector valve, a shaft for said selector valve, a motor for rotating said shaft at a relatively high speed when changing from one selector valve position to the next, a fuel pressure responsive switch for controlling said motor and thereby the rotation of said shaft, a cam on said shaft cooperating with said fuel pressure switch to open the switch when the shaft assumes a position of alignment of the ports of the selector valve providing fuel pressure has been built up in the fuel pressure switch, means for slowing down the operation of said motor when the selector valve has progressed to a position adjacent alignment of its ports, said means comprising a resistance connected in the circuit of said motor only when said shaft and thereby said selector valve assume said position adjacent alignment of the selector valve, a switch for each fuel tank and operable when the tank is empty to render said resistance ineffective to slow down said motor, and a commutator on said shaft and electrically connected in the circuits of said tank switches to permit only that tank switch which corresponds to an assumed selector valve position to render said resistance ineffective if the tank corresponding thereto is empty.

8. In an automatic safety fuel system having a plurality of fuel tanks, a selector valve connected between said plurality of fuel tanks and a fuel consuming device, a shaft for said selector valve, a motor for rotating said shaft at a relatively high speed when changing from one selector valve position to the next, a fuel pressure responsive switch for controlling said motor and thereby the rotation of said shaft, a solenoid, a switch therefore, a cam on said shaft cooperating with said last switch to energize said solenoid, said solenoid when energized opening said fuel pressure responsive switch when said selector valve shaft assumes a position of alignment of the ports of the selector valve providing fuel pressure has been built up in the fuel pressure switch, means for slowing down the operation of said motor when the selector valve has progressed to a position adjacent alignment of its ports, a switch for each fuel tank and operable when the tank is empty to render said last means ineffective to slow down said motor, and a commutator on said shaft and electrically connected in the circuits of said tank switches.

9. In an automatic safety fuel system having a plurality of fuel tanks, a selector valve for connecting said plurality of fuel tanks one at a time with a fuel consuming device, a motor for operating said selector valve at relatively high speed

when changing from one selector valve position to the next, a fuel pressure responsive switch for controlling said motor, an electrically operated clutch between said motor and said selector valve and controlled by said fuel pressure responsive switch, means for slowing down the operation of said motor when said selector valve has progressed to a position adjacent alignment of its ports, a switch for each fuel tank and operative when the tank is empty to render said last means ineffective, and a commutator operatively connected with said selector valve and electrically connected in the circuits of said tanks.

10. In an automatic safety fuel system having a plurality of fuel tanks and a fuel pump, a selector valve connected between said plurality of fuel tanks and said fuel pump, said fuel pump being operative to pump fuel to a fuel consuming device, a motor for operating said selector valve at relatively high speed when changing from one selector valve position to the next, a fuel pressure responsive switch for controlling said motor, an electrically operated clutch between said motor and said selector valve and controlled by said fuel pressure responsive switch, means for slowing down the operation of said motor when said selector valve has progressed to a position adjacent alignment of its ports, and means for opening said fuel pressure responsive switch at port alignment position.

11. In an automatic safety fuel system including a plurality of fuel tanks and a fuel pump, a selector valve connecting any one of said plurality of fuel tanks with said fuel pump, a motor for operating said selector valve at relatively high speed when changing from one selector valve position to the next, a fuel pressure responsive switch for controlling said motor, an electrically operated clutch between said motor and said selector valve and controlled by said fuel pressure responsive switch, means for slowing down the operation of said motor when said selector valve has progressed to a position adjacent alignment of its ports, a switch for each fuel tank, a commutator operatively connected with said selector valve and electrically connected with the circuit of each of said tank switches, and a relay connected in circuit with said commutator, said relay being operative to render said means for slowing down the operation of said motor ineffective.

12. In an automatic safety fuel system of the class described having a plurality of fuel tanks, a selector valve connected between said fuel tanks and a fuel consuming device, a motor for operating said selector valve at relatively high speed when changing from one selector valve position to the next, a fuel pressure responsive switch for controlling said motor, means for slowing down the operation of said motor when said selector valve has progressed to a position adjacent alignment of its ports, a switch for each fuel tank, a commutator operatively connected with said selector valve and electrically connected with the circuit of each of said tank switches, and a relay connected in circuit with said commutator and tank switches, said relay being operative to render said means for slowing down the operation of said motor ineffective.

13. In an automatic safety fuel system having a plurality of fuel tanks and a fuel pump, a selector valve connected between said plurality of fuel tanks and said fuel pump, said pump being operative to pump fuel to a fuel consuming device, a motor for operating said selector valve at relatively high speed when changing from one

selector valve position to the next, a fuel pressure responsive switch for controlling said motor, and means for slowing down the operation of said motor when said selector valve has progressed to a position adjacent alignment of its ports.

14. In an automatic safety fuel system having a plurality of fuel tanks and a fuel pump, a selector valve for selectively connecting any one of said fuel tanks with said fuel pump, means for operating said selector valve at relatively high speed when changing from one selector valve position to the next, a fuel pressure responsive controller for controlling said means, means for slowing down the operation of said first means when said selector valve has progressed to a position adjacent alignment of its ports, and means for operatively disconnecting said first means from said selector valve at port registering position, said last means being controlled by reason of said controller being operatively connected with said selector valve to be actuated to inoperative position thereby upon said selector valve assuming said port registering position.

15. In an automatic safety fuel system having a plurality of fuel tanks and a fuel pump, a selector valve for selectively connecting said plurality of fuel tanks with said fuel pump, said fuel pump being operative to pump fuel to a fuel consuming device, a motor for operating said selector valve at relatively high speed when changing from one selector valve position to the next, a switch for controlling said motor, said switch being responsive to fuel pressure supplied by said pump in conjunction with positioning of said selector valve at port alignment position, and means for slowing down the operation of said motor when said selector valve has progressed to a position adjacent said port alignment position, said switch, in response to selector valve position, de-energizing said motor.

16. In an automatic safety fuel system having a plurality of fuel tanks and a selector valve connected between said plurality of fuel tanks and said fuel pump, a motor for operating said selector valve at relatively high speed when changing from one selector valve position to the next, a fuel pressure and selector valve position responsive switch for controlling said motor, an electrically operated clutch for operatively connecting said motor with said selector valve, said clutch being under control of said fuel pressure responsive switch, and means synchronized with the operation of said selector valve for slowing down the operation of said motor when said selector valve has progressed to a position adjacent alignment of its ports.

17. In an automatic safety fuel system including a plurality of fuel tanks, a selector valve connected between said plurality of fuel tanks and a fuel consuming device, a motor for operating said selector valve at relatively high speed when changing from one selector valve position to the next, a fuel pressure and selector valve position responsive switch for controlling said motor, and selector valve position responsive means for slowing down the operation of said motor when said selector valve has progressed to a position adjacent alignment of its ports.

18. In an automatic safety fuel system including a plurality of fuel tanks and a fuel pump, a selector valve connecting any one of said plurality of fuel tanks with said fuel pump, a motor for operating said selector valve at relatively high speed when changing from one selector valve position to the next, a fuel pressure responsive switch

for controlling said motor, said fuel pressure responsive switch being closed by a drop of fuel pressure and carried in closed position to another position upon subsequent building up of fuel pressure, a solenoid for opening said switch when in said another position, means for controlling said solenoid comprising a switch operated in synchronism with said selector valve, and means for slowing down the operation of said motor when said selector valve has progressed to a position adjacent alignment of its ports.

19. In an automatic safety fuel system having a plurality of fuel tanks, a selector valve connected between said fuel tanks and said fuel pump, said fuel pump being operative to pump fuel to a fuel consuming device, a motor for operating said selector valve normally at relatively high speed, a fuel pressure responsive switch for controlling said motor, said fuel pressure responsive switch being closed by a predetermined drop of fuel pressure from said pump and carried in closed position to another position upon subsequent return of fuel pressure to a predetermined degree, means for opening said switch when in said another position, means operated in synchronism with the rotation of said selector valve for controlling said last means, and means for slowing down the operation of said motor when said selector valve has progressed to a position adjacent alignment of its ports.

20. In an automatic safety fuel system having a plurality of fuel tanks and a fuel pump, a selector valve for selectively connecting any one of said plurality of fuel tanks with said fuel pump, said fuel pump being operative to pump fuel to a fuel consuming device, a motor for operating said selector valve at relatively high speed when changing from one selector valve position to the next, a fuel pressure responsive switch for controlling said motor, said fuel pressure responsive switch being closed by a drop of fuel pressure and carried in closed position to another position upon subsequent rise of fuel pressure, means operated in synchronism with the rotation of said selector valve for opening said switch when in said another position, and means for slowing down the operation of said motor when said selector valve has progressed to a position adjacent alignment of its ports.

21. In an automatic safety fuel system having a plurality of fuel tanks and a fuel pump, a selector valve connected between said plurality of fuel tanks and said fuel pump, said fuel pump being operative to pump fuel to a fuel consuming device, a motor for operating said selector valve at high speed from one selector valve position to the next, a fuel pressure responsive switch for controlling said motor, an electrically operated clutch connection between said motor and said selector valve, said clutch connection being under control of said fuel pressure responsive switch, and means responsive to selector valve position for slowing down the operation of said motor as said selector valve closely approaches port alignment position.

22. In an automatic safety fuel system having a plurality of fuel tanks and a fuel pump, a selector valve for selectively connecting any one of said plurality of fuel tanks with said fuel pump, said fuel pump being operative to pump fuel to a fuel consuming device, a motor for quickly operating said selector valve from one selector valve position to the next, means under control of said selector valve to slow down said motor at adjacent port alignment position of the

valve, a fuel pressure and selector valve position responsive switch for controlling said motor, and an electrically operated clutch connection between said motor and said selector valve, said clutch connection being under control of said fuel pressure responsive switch.

23. In an automatic safety fuel system having a plurality of fuel tanks and a fuel pump, a selector valve connected between said plurality of fuel tanks and said fuel pump, said fuel pump being operative to pump fuel from said valve to a fuel consuming device, a motor for operating said selector valve at relatively high speed when changing from one selector valve position to the next, a fuel pressure responsive switch for controlling said motor, a shunting switch in the circuit of said motor, a resistance shunting said switch, said shunting switch being opened by said selector valve when adjacent port registering position whereby to slow down the rotation of said selector valve, a switch for each fuel tank, a commutator connected with said selector valve and electrically connected in the circuits of said tank switches, and a relay controlled by said commutator and shunting said resistance to effect relatively high speed rotation of said selector valve past a port registering position corresponding to an empty fuel tank.

24. In an automatic safety fuel system having a plurality of fuel tanks, a selector valve connected between said plurality of fuel tanks and a fuel consuming device, a motor for operating said selector valve at high speed when changing from one selector valve position to the next, a fuel pressure responsive switch for controlling said motor, and a shunting switch in the circuit of said motor, a resistance shunting said switch, said shunting switch being opened by said selector valve when adjacent port registering position whereby to slow down the rotation of said selector valve.

25. In an automatic safety fuel system having a plurality of fuel tanks, a selector valve for selectively connecting any one of said plurality of fuel tanks with a fuel consuming device, a motor for operating said selector valve at high speed when changing from one selector valve position to the next, a fuel pressure responsive switch for controlling said motor, a shunting switch in the circuit of said motor, a resistance shunting said switch, said shunting switch being opened by said selector valve when adjacent port registering position whereby to slow down the rotation of said selector valve, a switch for each

5 fuel tank, and a commutator operatively connected with said selector valve and electrically connected in the circuits of said tank switches, said commutator and tank switches effecting shunting of said resistance to effect high speed rotation of said selector valve past a port registering position corresponding to an empty fuel tank.

26. In an automatic safety fuel system having a plurality of fuel tanks and a fuel pump, a selector valve connected between said plurality of fuel tanks and said fuel pump, said fuel pump being operative to pump fuel to a fuel consuming device, a motor for operating said selector 10 valve at high speed when changing from one selector valve position to the next, a fuel pressure and selector valve position responsive switch for controlling said motor, a second switch in the circuit of said motor, means responsive to said second switch when said selector valve approaches port registering position to slow down the rotation of said motor and thereby said selector valve, a switch for each fuel tank, a commutator connected with said selector valve and electrically connected in the circuits of said tank switches, and a relay controlled by said commutator and tank switches operable when energized to render ineffective said means responsive to said second switch whereby to cause said selector valve to pass at high speed a port registering position corresponding to an empty fuel tank.

27. In an automatic safety fuel system of the character disclosed having various fuel tanks, a selector valve for connecting said various fuel tanks with a fuel consuming device, a motor for operating said selector valve at high speed when changing from one selector valve position to the next, a fuel pressure and selector valve position responsive switch for controlling said motor, a second switch in the circuit of said motor, means responsive to said second switch when said selector valve approaches port registering position to slow down the rotation of said motor and thereby said selector valve, a switch for each fuel tank, a commutator connected with said selector valve and electrically connected in the circuits of said tank switches and operable to render ineffective said means for slowing down said motor whereby to cause said selector valve to pass at high speed a port registering position corresponding to an empty fuel tank.

DAVID SAMIRAN.
